ARTICLE-WORKING APPARATUS

Gilbert J. Lamoureux, Chicago, Ill., assignor to Western Electric Company, Incorporated, New York, N. Y., a corporation of New York

Application December 21, 1954, Serial No. 476,654

2 Claims. (Cl. 18—19)

This invention relates to article-working apparatus, and more particularly to apparatus for forming embossed plastic washers.

An object of the invention is to provide apparatus for simultaneously forming plastic washers with embossed portions attached to frusto-conical portions.

Another object of the invention is to provide apparatus for perforating a sheet of plastic sheet material, forming an embossed portion surrounding the perforations and cutting the formed portions from the sheet.

A further object of the invention is to provide apparatus for forming embossed slit conical washers.

An apparatus illustrating certain features of the invention may include a pair of relatively movable dies for sequentially cutting a disc from a plastic sheet and embossing the central portion of the disc. Further means are provided for punching out the central portion of the embossed portion of the disc and slitting the disc.

A complete understanding of the invention may be obtained from the following detailed description of an apparatus forming a specific embodiment thereof, when read in conjunction with the appended drawings, in which

Fig. 1 is a top plan view of an article formed by an apparatus forming one embodiment of the invention;

Fig. 2 is a vertical section of an apparatus forming one embodiment of the invention, and

Fig. 3 is a vertical section taken along line 3—3 of Fig. 2.

Referring now in detail to the drawings, there is shown therein an apparatus for forming a washer 10 having a frustoconical peripheral portion 11 having a slit 12 therein and a generally cylindrical portion 13. The washers 10 are formed from a sheet 14 of thermoplastic material such as, for example, cellulose acetate, which is fed by a feed mechanism 15 of a well known type step-by-step to and through a punch 16 operable in synchronism with the feeding. The punch 16 includes a frame 21 mounted on a solid foundation 22 and having a bore 23 therein in which a pressure or annular forming and cutting punch or sleeve 24 having a frustoconical punch surface is slidably mounted, the downward movement of the sleeve 24 being keyed through a slot 25 and a key 26 secured to the sleeve 24. The sleeve 24 is provided with a frustoconical end surface and a circular cutting edge 31 which cooperates with a fixed cutting edge 32 of a lower fixed blanking die 33. A drawing sleeve or die 41 having a frustoconical end portion is mounted slidably in a bore 42 in the sleeve 24. A flange 45 of the sleeve 41 is urged continuously downwardly in a counterbore 46 in the sleeve 24 by a spring 47 pressing at its upper end thereagainst a head 48 on a perforating punch 49. A pin 55 secured to the sleeve 24 projects through a slot 56 in the head 48 to key these elements, and a retracting or lifting roller 61 is mounted rotatably on a pin 62 fixed to the sleeve 24.

When a lever 71 is moved downwardly, it presses against the head 48 to press the punch 49 through a perforating opening 70 of a fixed perforating and drawing

2

punch 72 to punch a disc 85 from the sheet, the sleeves 24 and 41 abutting a forming and stripping punch or sleeve 73 having a frustoconical end surface urged upwardly by a compression spring 74 mounted on a collar 75 of the punch 72. The springs 47 and 74 function as a lost motion means because the spring 47 is substantially weaker than the spring 74, and, after the perforating, the sleeve 41 engages and is held against movement by the punch 73 until the sleeve 24 also engages the sheet 14 and presses it against the punch 73. The sleeve 24 then blanks the washer 10 and pushes the punch 73 downwardly against the action of the spring 74, and the sleeve 41 moves downwardly simultaneously with the sleeve 24 through the action of a shoulder 79 on the punch 49 to draw the cylindrical portion 13 with the fixed drawing punch 72. A thrust ring 78 transmits force from the punch 49 to the sleeve 24. The sleeves 24 and 41 and the punches 72 and 73 are heated by a heating element 81 controlled by a thermocouple 82 to a temperature that the washer 10 is heated sufficiently to form it permanently to the shape in which it is shown in the drawings. Then, as the lever 71 moves further downwardly, the washer 10 is moved against a knife blade 91 mounted on the die 33 projecting into a slot 92 in the punch 73, and the knife blade 91 forms the slit 12 of the peripheral portion 11 of the washer. Then when the lever 71 is raised, the punch 49 is extracted from the washer 10, the sleeves 41 and 24 retract backwardly out of contact with the washer, and the washers are pushed upwardly by the punch 73 off of the drawing punch 42 and out of a bore 95 forming a guide for the punch 73. A key 96 fixed to the die 33 projects into a slot 97 to key the punch 73 to the die 33.

The above-described apparatus serves to precisely form, draw, cut and slit the washers 10 and is simple and inexpensive in construction and highly effective in its operation.

It is to be understood that the above-described arrangements are simply illustrative of the application of the principles of the invention. Numerous other arrangements may be readily devised by those skilled in the art which will embody the principles of the invention and fall within the spirit and scope thereof.

What is claimed is:

1. A plastic material working apparatus, which comprises a fixed perforating and drawing punch having an open cylindrical projection therein, a blanking die, a slotted forming and stripping punch having a frustoconical end surface mounted slidably on the drawing punch and in the blanking die, a knife rigidly mounted on the blanking die and projecting into the slot of said stripping punch, a drawing sleeve having a frustoconical surface to cooperate with the said stripping punch and designed to slide over the end of the drawing punch with clearance therebetween to provide for the formation of an embossed surface to project from the surface of the plastic material, a forming and cutting sleeve mounted slidably over the drawing sleeve and having a frustoconical end to cooperate with the stripping punch so as to grip the plastic material therebetween, said forming and cutting sleeve mounted on the exterior of the drawing sleeve with a cutting edge on its periphery for cutting a disc from the plastic material, a perforating punch carried slidably in the drawing sleeve for cooperating with the drawing punch to perforate the disc, lost-motion means connecting the punch to the drawing sleeve and the forming and cutting sleeve, and means for heating the frustoconical surfaces to soften the plastic material.

2. An article working apparatus, which comprises a solid cylindrical punch with a reduced cylindrical end section, a drawing sleeve slidably mounted on said solid cylindrical punch in sliding contact with the larger cylind-

drical portion thereof and having a frustoconical end surface, a cutting sleeve slidably mounted in concentric relation to the drawing sleeve and having frustoconical end surfaces, a stationary perforating and drawing punch with a cylindrical end portion to cooperate with the outer surface of the reduced portion of the cylindrical punch to perforate plastic sheet material and to form an embossed portion to project from the surface of the disc to be formed and to be adjacent the perforated opening of the disc, a stripping punch slidably mounted in concentric relation to the stationary perforating and drawing punch and in alignment with the cutting sleeve, said stripping punch having a frustoconical end surface to cooperate with the frusto conical end surface of the drawing sleeve and cutting sleeve to grip the plastic material to be formed therebetween, said stripping punch having a slot to permit a stationary knife blade to pass therein, a blanking die slidably mounted in concentric

10

15

relation to the stripping punch so as to cooperate with the cutting sleeve to cut the blank from plastic sheet material, a knife rigidly mounted to the said blanking die and projecting into the slot in the stripping punch and cooperating with the frustoconical surface of the cutting punch to slit the disc radially for a predetermined distance, lost-motion means connecting the solid cylindrical punch to the drawing sleeve and the cutting sleeve, and means for heating the drawing sleeve and punches to soften the plastic material.
